US0D1020085S

(12) United States Design Patent (10) Patent No.: US D1,020,085 S
(45) Date of Patent: * Mar. 26, 2024

(54) DETANGLING COMB

(71) Applicant: Temilola Sulu, London (GB)

(72) Inventor: Temilola Sulu, London (GB)

() Term: 15 Years

(21) Appl. No.: 35/517,303

(22) Filed: May 5, 2023

(80) Hague Agreement Data

Int. Filing Date: May 5, 2023

Int. Reg. No.: DM/228925

Int. Reg. Date: May 5, 2023

Int. Reg. Pub. Date: May 26, 2023

(51) LOC (14) Cl. 28-03

(52) U.S. Cl.

USPC D28/28; D4/136

(57) CLAIM

The ornamental design for a detangling comb, as shown and described.

DESCRIPTION

1. Detangling comb
2. Detangling comb
- 1.1 : Back
- 1.2 : Front
- 1.3 : Perspective
- 1.4 : Bottom
- 1.5 : Perspective
- 1.6 : Left
- 1.7 : Right
- 1.8 : Top
- 2.1 : Top
- 2.2 : Back
- 2.3 : Perspective

2.4 : Bottom

2.5 : Front

2.6 : Left

2.7 : Right

2.8 : Perspective

No claim is made for the shape of handle of the detangling combs shown in the drawings.

1 Claim, 16 Drawing Sheets
